UNITED STATES PATENT OFFICE.

JOHN H. DITCH AND WILLIAM T. BURNS, OF ALTOONA, PENNSYLVANIA.

TELEPHONE SWITCHING-CABINET.

1,371,874.

Specification of Letters Patent. Patented Mar. 15, 1921.

Application filed January 25, 1916. Serial No. 74,209.

To all whom it may concern:

Be it known that we, JOHN H. DITCH and WILLIAM T. BURNS, citizens of the United States, residing at Altoona, in the county of Blair and State of Pennsylvania, have invented certain new and useful Improvements in Telephone Switching-Cabinets, of which the following is a specification.

This invention primarily relates to telephones, and particularly to telephone switching cabinets in railway block offices wherein the telephone has superseded the telegraph as a means of communication between points within the block, or from places out of the same.

One of the objects of the invention is to provide a push key operated telephone switching cabinet such that its functions will not be in any way interfered with when making repairs to the line or cabinet connections.

A further object of the device is to provide a telephone switching cabinet that is of a durable, compact construction, having all the various parts easily accessible and maintained.

With the above and other objects in view which will more readily appear as the nature of the invention is better understood, the same consists in the novel construction, combination and arrangement of parts herein-after more fully described, illustrated and claimed.

A preferred and practical embodiment of the invention is illustrated in the accompanying drawings, in which—

Figure 1 is a front elevation of the improved cabinet.

Fig. 2 is an end view of the cabinet shown in Fig. 1.

Fig. 3 is a sectional view of the cabinet and clearly illustrates the telephone push keys, telephone jack, and annunciator.

Fig. 4 is a plan view of the telephone switching cabinet with the cabinet cover removed, showing the arrangement of annunciators, push keys and locking devices.

Fig. 5 is a front elevation illustrating the annunciator rack thrown up for accessibility and inspection.

Fig. 6 is a horizontal view taken on the line 6—6 of Fig. 3.

Fig. 7 is an end view of the cabinet as shown in Fig. 5.

Fig. 8 is a sectional view of the push key locking bar.

Fig. 9 shows a front elevational view of

the locking bar, the keys being shown in section.

Similar reference characters designate corresponding parts throughout the several figures of the drawings.

In carrying out this invention, no change is contemplated in the usual type of telephone, nor any of its associated parts which are essential for the perfect transmission of sound waves, but our invention is directed to a cabinet for conveniently supporting and housing a push key interlocking device associated with a telephone jack and telephone annunciator in a manner such as to automatically connect the telephone to any one of a number of telephone lines terminating in a cabinet so constructed as to provide terminals for a plurality of different lines, each line being associated with a key in the cabinet which, when pushed, automatically locks the telephone to the line and simultaneously restores the signal, as well as locking itself in the pushed position, to be released by pushing in another key or the shifting by hand of the locking means itself.

Accordingly, to this end, we employ a telephone cabinet 10 having positioned therein a hinged frame 11, carrying a plurality of push keys 12, each of which cooperates with a telephone jack device designated generally as 13, and having a suitable call annunciator 14, which is permitted to move when the call is made and is restored to its operative position through the co-operation of the particular push key 12 associated with the jack device.

For the purpose of keeping or locking the telephone to the line, a suitable key actuated keeper bar is provided, the same being designated by the reference character 15 and shown more clearly in Figs. 8 and 9, although shown in its assembled relation to the other cabinet parts in Figs. 1, 3, 4, and 100.5. This bar 15 is provided with a plurality of horizontally elongated openings that receive the shank portions of the keys 12, which latter, in addition to having the head portion 12^a, carry a cone collar 12^b adapted to have a camming engagement with the sides of the openings in the keeper bar. One end of the bar is provided with an offset handle portion 15^a which may be engaged by the operator to shift the bar laterally to disengage it from the key which it holds in a "pushed in" position to release the same from the line terminals *m*—*m*. However, the releasing of a key 12 may also be effected

by the pushing in of another key. For instance, assume that one of the keys 12 is pushed in, its cone collar will cause the bar to move to the right, until the said cone has passed clear through the opening, then the bar, by virtue of a spring 15^b, will be pulled back to its normal position and the key will be maintained at the end of its inward limit, because of the shoulder of the cone collar 10 engaging the inner face of the bar. Then if another key is pushed in, the bar will again be pushed to the right thereby bringing the opening through which the first key passed in such a position that the said key, 15 which has been locked in, may jump back to its normal position. If it is desired to release the key before another key is pushed in, the operator may shift the bar laterally by pushing the handle projection 15^a. Accordingly, it will be understood that a key 20 which is pushed in can only be released by pushing the bar to the right against the tension of the spring 15^b by hand or by pushing in another key which performs the same function.

Referring to Fig. 5, the first four terminals 24 are connected to the annunciators or drops, the second four 24^a are connected to the selector circuits, the selectors of which 30 are operated by currents of different intensity, each selector responding to certain fixed impulses sent out by the operator. The fifth pair 25, connects the night alarm bell with all the jacks and with each night alarm contact on the annunciator, and the sixth pair 35 26 connects with the interrupter primary, while the seventh pair 27 of terminals connect with the interrupter secondary; the function of which is to furnish ringing current to the telephone line at the option of 40 the cabinet operator.

The ringing key 16, when pushed by the operator, has the function of energizing the primary coil of the interrupter by connecting the direct current from a battery to the 45 primary winding. An induced alternating current is thus established in the secondary winding of the interrupter, and the ringing action is thus accomplished.

50 The main telephone set is represented by the eighth pair of terminals, designated by the numeral 28, Fig. 5, and is associated with what is termed an emergency jack 29. In case of trouble with the main telephone set designated by the numeral 28, the operator plugs in at 29 and the main set is thus 55 cut out, then with the opposite end of the cord the operator plugs in at 29^a thus connecting to the extra set.

60 The ninth pair of terminals, designated by the numeral 30 is wired in connection with the extension bell, the function of which will be explained later in the specification. The tenth pair of terminals, designated by the numeral 31, is connected to the

extra set which provides means for the operator plugging in on the extra set and thereby connecting the party to the line over which he wishes to talk, while the operator is performing other duties.

70 The plug receptacles 32 provide means for allowing the operator to connect two lines together with the usual plug and cord, thus establishing a telephone circuit in an independent manner, while the operator is free 75 to perform other duties in connection with the proper handling of calls which arise on the various lines that terminate in the cabinet.

The extension bell set, connected to the 80 ninth pair of terminals designated by the numeral 30, may be termed an auxiliary indicating device, and its function is manifested in case the operator, after talking over a line, neglects to release the indicator 85 or push the key, and a party on the line just used wishing to call the operator would cause the ringing of the extension bell, thus notifying the operator that some one wished to again use the line.

90 From the above description, together with the drawings, it will be apparent without further elaboration that this improved device completely provides for the adaptation of a push key device to be assembled in a 95 suitably formed cabinet wherein are installed telephone jacks and annunciators or drops, in such manner and with such other necessary apparatus as to form a complete 100 device for the use of a plurality of telephones and one or more telephone lines, as now in daily use in railway block signal systems of the most modern railroads.

105 From the foregoing, it is thought, that the many features and advantages of the present invention will be readily apparent, and it will, of course, be understood that various changes in the form, proportion, and minor details of construction may be resorted to without departing from the spirit of the 110 invention or scope of the appended claim.

We claim:

A telephone exchange cabinet including a 115 hinged cover, a face plate member adapted to carry all of the push keys and means for locking the individual push keys in their pushed-in position, a longitudinal panel-strip carried by the base of the cabinet along the front thereof and adapted to operate with the face plate to form the entire front of the cabinet, and a plurality of 120 plug receptacles carried by said panel-strip.

In testimony whereof we affix our signatures in presence of two witnesses.

JOHN H. DITCH.
WILLIAM T. BURNS.
